UNITED STATES PATENT OFFICE.

THADDEUS C. BEATTY, OF LYNNVILLE, IOWA.

SANITARY ROOST AND NEST.

Application filed January 11, 1922. Serial No. 528,544.

To all whom it may concern:

Be it known that I, THADDEUS C. BEATTY, a citizen of the United States, and resident of Lynnville, in the county of Jasper and 5 State of Iowa, have invented a certain new and useful Sanitary Roost and Nest, of which the following is a specification.

The object of my invention is to provide a simple, durable and sanitary roost construction designed to be used in poultry houses.

A further object is to provide an improved poultry roost detachably mounted in a container designed to carry disinfectant, so arranged that the said roost may be 10 moved and the disinfectant renewed.

A further object is to provide improved means for supporting a poultry roost formed of sheet metal and designed to carry detachable roost members formed of a non-heat 15 conducting material.

A further object is to provide a sanitary support designed to carry detachable roost members formed of non-heat conducting material and also sanitary nest boxes.

20 These and other objects will be apparent to those skilled in the art.

My invention consists in the construction, arrangement and combination of the various parts of the device, whereby the objects contemplated are attained, as hereinafter more 25 fully set forth, pointed out in my claims, and illustrated in the accompanying drawings, in which:

Figure 1 is a plan view of my improved 30 nest and roost device showing the same applied to the interior of a building wall, the said roost being broken away through the center.

Figure 2 is a sectional view taken on the 35 line 2—2 of Figure 1 showing part of the nest in section and the other part in an end elevation.

Figure 3 is a vertical central sectional view taken on the line 3—3 of Figure 2.

40 The numeral 10 indicates the walls of a poultry house which are shown in segments in the various views. These walls are usually formed of a series of vertically arranged boards set edge to edge and held in position 45 by means of suitable frame work.

The numeral 11 indicates the side walls, and the numeral 12 indicates one of the ends.

Secured to each of the side walls 11, I

have provided horizontally arranged strips 13. These strips 13 are preferably arranged 55 on the back ends of the side members 11 so that the roost construction may be placed in the back end of the building.

Mounted transversely on these strips 11, I have mounted my improved roost and nest 60 construction, which is formed preferably of galvanized sheet metal. This construction comprises members 14 formed with flanges 15 so as to resemble a channel iron. The members 14 are of such length that their 65 ends will rest upon the members 13, as clearly shown in Figures 2 and 3. There is preferably two of these members, one at the back and one at the front end of the strips 13.

Mounted on the top of each of the members 14 and near each of its ends, I have provided a bracket member 16 formed of pressed sheet metal and galvanized. These brackets are riveted to the upper flanges 15.

Mounted at equal intervals between the 75 brackets 16, I have provided somewhat larger brackets 17 also formed of pressed sheet metal, each of which is provided with a notch 18 in its upper surface. These brackets are spaced apart a distance, preferably 80 about fourteen inches, the brackets on the back member 14 being in line with those on the front member 14.

Mounted in each corresponding set of brackets, I have provided a trough 19 having sides 30 and a bottom 21. This trough 85 is also provided with end members 22 and is formed of sheet metal.

By this arrangement it will be seen that I have provided a series of troughs which 90 extend parallel with each other and spaced apart a distance substantially fourteen inches apart. These troughs may be of any desired length.

Detachably mounted in each of said 95 troughs 19, I have provided a roost member 23 formed preferably of 2 x 4 studdings set on edge, the upper edge of said studdings extending above the upper edge of the troughs 19 a considerable distance so that 100 the fowls may be provided with a non-heat conducting material upon which they may roost without having their feet frozen in the winter time.

Before the roosts are placed in position, 105 a small quantity of liquid disinfectant may

be placed in each of the troughs so as to insure the fowls against vermin, the members 23 being made of a slightly less width than the width of the troughs so that space 5 will be permitted for the vermin to crawl between the sides 20 and the sides of the members 23.

Mounted upon and secured between the adjoining edges of two of the troughs 19, I 10 have provided curved plates 24, the edges of each of said plates being provided with flanges 25 which hook over the upper edges of the side members 20.

These plates are formed with their concave 15 sides up, while the central portion of their convex sides rests on the top of the members 14. The said plates are designed to take the place of the drop boards.

Secured longitudinally beneath the central 20 portion of each of the plates 24, I have provided a vertical plate 26 having a flange 27 at each of its ends which are riveted to the members 14. The upper edge of the plates 26 is provided with a flange 28 which is riveted to an adjacent plate 24. These plates 25 26 are considerably shorter than the members 19 and are secured adjacent to the front member 14, as clearly shown in Figure 3, and are designed to form the side members 30 of the nest. The lower edge of each of the plates 26 is provided with a flange 29.

Pivotedly mounted beneath the front member 14, I have provided an end plate 30 designed to be swung forwardly and upwardly for the purpose of removing the eggs from the nest. This plate may be of a length equal to the width of the rows of nests, or an individual door might be provided for each nest. A bottom member 31 35 is provided which is hinged to the flanges 29 at their back ends, the front end of the said member being secured against downward movement by a suitable hook 32. This bottom 31, as in the case of the member 30, 40 may be made to extend the full length of the nest or one for each individual nest. The spaces between the plate members 26 45 are left open.

By this arrangement, I have provided a 50 series of nests beneath the plates 24 which are constructed entirely of sheet metal and provided with a hinged bottom 31 which may be unhooked at its forward edge and allowed to swing to a vertical position, at 55 which time any litter or nest material may be emptied to the ground. The bottom may be then hooked to its horizontal position and new and clean nest material may be placed through the doorway by opening 60 the door 30. The door 30 also serves the purpose as before stated of removing the eggs from the nest.

Thus it will be seen that I have provided a nest having a top, a bottom, two sides and one end closed, the back end of the nest being 65

open which is beneath the central portion of the plates 24. In poultry houses of this construction, the light usually enters the front. This provides a comparatively dark nest for the fowls which makes a very desirable and attractive place for their nest. 70

By this construction, it will be seen that I have provided a roost support, the plates 24 and the nest members riveted and secured together as a unit formed of a material 75 which may be easily and quickly cleansed by removing the entire construction from the building and applying water by a hose and by scrubbing. The water will in no way hurt the metal. 80

It will also be seen that the plates 24 may be easily and quickly cleaned by applying a scraper and moving it longitudinally with the plates when the said plates are in position within the building. 85

Another advantage of this construction lies in the fact that the entire structure may be removed from the building so that the attendant may enter the building and clean it without having to reach under or stoop, 90 as the roost and the plates 24 are preferably mounted about two and one-half or three feet above the floor so that the space above them may be utilized for roosts, while the space below may be utilized for floor space 95 in which the fowls may exercise.

I claim as my invention:

1. The combination of a series of metallic supports, a series of parallel troughs mounted on said supports, a detachable roost member mounted in each of said troughs, each of said troughs being designed to receive a disinfectant, a series of concave plates mounted on the upper edge of said troughs extending parallel with said roosts, a vertically arranged plate secured to the bottom of each of said concave plates, a hinged bottom member secured to the bottom of said vertical plates, a door member secured to the bottom of one of said supports adjacent 100 to one end of said vertical plates. 105

2. A roost construction formed of sheet metal comprising supports, a series of parallel troughs mounted on said supports, a detachable roost member mounted in each 110 of said troughs, said troughs being designed to contain a disinfectant, a curved dropping plate mounted between and on the top edge of said troughs. 115

3. A roost construction formed of sheet 120 metal comprising supports, a series of parallel troughs mounted on said supports, a detachable roost member mounted in each 125 of said troughs, said troughs being designed to contain a disinfectant, a curved dropping plate mounted between and on the top edge of said troughs, nest members supported by said plates, a hinged bottom member for said nest members, and a hinged front member for said nest members. 130

4. The combination of a poultry wall having supporting strips, a metallic unitary roost and nest construction comprising supports, a series of parallel troughs on said supports, a series of concave dropping plates between said troughs, a detachable roost member mounted in said troughs, said troughs being designed to receive disinfectant, a series of nest members mounted beneath said concave plates, a bottom member 10 for said nest members, and a pivoted front member, the nest members being of a considerably less length than the roost members.

THADDEUS C. BEATTY.
